UNITED STATES PATENT OFFICE.

ANTONIO D'AGOSTINO, OF UTICA, NEW YORK, ASSIGNOR OF ONE-HALF TO NICHOLAS GENTILE, OF LAWRENCE, MASSACHUSETTS.

SAFETY-ENVELOP.

1,171,323.

Specification of Letters Patent.

Patented Feb. 8, 1916.

Application filed February 17, 1915. Serial No. 8,805.

To all whom it may concern:

Be it known that I, ANTONIO D'AGOSTINO, a citizen of the United States of America, residing at Utica, in the county of Oneida and State of New York, have invented certain new and useful Improvements in Safety-Envelops; and I do hereby declare the following to be a full, clear, and exact description of the invention, such as will enable others skilled in the art to which it appertains to make and use the same.

This invention relates to safety envelops, the object of the same being to provide an envelop of simple construction which can not be opened without mutilating the paper and indicating that the envelop has been tampered with by an unauthorized person.

The foregoing and other objects may be attained by means of the construction illustrated in the accompanying drawing, in which—

Figure 1 is a plan view of the blank from which the envelop is made looking at the inner side of the blank, Fig. 2 is a view looking at the face side of the envelop with the sealing flap unattached or unsealed, Fig. 3 is a fragmentary section of the envelop in sealed condition and before the stamp has been applied, and Fig. 4 is a sectional view taken on the line 4—4 of Fig. 3 and made on a larger scale and showing the stamp attached to the envelop.

Referring to the drawing, the numeral 1 designates the body portion of the envelop, 2 designates a side flap having a straight upper edge 3, and a curved lower edge 4. At the opposite side of the body portion 1 is a smaller flap 5 having a curved upper edge 6 and a straight lower edge 7, the outer edge 40 of the flap being plain as shown at 8. At the lower side of the body portion 1 is a sealing flap 9 provided with an adhesive substance 10 extending around the outer edge thereof and said flap being slightly offset from the center of the body portion 1 and having a curved line 11 on one side and a compound curved line 12 upon the other side, while the end 13 is plain.

The face portion 14 of the envelop is rectangular in form and is of substantially the same size and form as the body portion 1 of

the envelop. Upon the right hand upper corner of the face portion 14 when folded is a rectangular opening 15 having a V-shaped projection 16 extending from the inner edge of the opening. The face portion 14 is also provided with adhesive substance 17 on the inner face thereof around the edges. 55

In folding the envelop, the flap 2 is first folded on the dotted line *a* against the body portion 1. The flap 5 is then folded upon the dotted lines *b* against the body portion 1. The sealing flap 9 is then folded on the dotted line *c* upward and secured by the adhesive material 10 to the edges of the flaps 2 and 5. When the letter or missive *d* is inserted in the envelop, the face portion 14 is folded along the dotted line *e*, thus bringing the opening 15 over a portion of the side flap 5 and over a portion of the missive *d*. When 60 the stamp *f* in Fig. 4 is attached to the envelop and disposed over the opening 15, a portion of the stamp will be connected to the missive *d*, to the tongue 16, and to the marginal portion of the opening 15, as well as to 65 a portion of the flap 5. The curved line 6 of the flap 5 extends diagonally across underneath the opening 15, as shown in Fig. 3, when the envelop is folded and ready to be mailed. 70 75 80

From the foregoing it will be obvious that the contents of the envelop cannot be removed for inspection without mutilating the envelop.

Various changes may be made in the details of construction without departing from the spirit and scope of the invention as defined in the claims.

What is claimed is:—

A safety envelop having a body, a side 90 flap, having a straight upper edge and an inclined lower edge, a smaller side flap formed on the opposite side of the body, said smaller side flap having a curved upper edge and an inclined lower edge, a bottom sealing 95 flap having adhesive material around the edges thereof, and a face portion substantially rectangular in form provided with an opening somewhat smaller than a postage stamp at the right hand upper corner, said 100 opening being provided with an extended tongue and said face portion folded up

against the side and bottom flap, a portion of the contents of the envelop will be exposed through the opening so that when a postage stamp is attached thereto it will adhere to the contents to one of the side flaps as well as the face portion, thereby preventing the same from being opened without detection.

In testimony whereof I affix my signature in presence of two witnesses.

ANTONIO D'AGOSTINO.
